GRINDING MACHINE

Franz Neugart, Berlin-Charlottenburg, Germany

Application April 11, 1938, Serial No. 201,386
In Germany April 12, 1937

2 Claims. (Cl. 51—95)

My invention relates to grinding machines, and more particularly to grinding machines of that type in which a grinding wheel is mounted to rotate on a swinging bracket, and a truing tool for the grinding wheel is arranged with its point on the arc described by the perimeter of the grinding wheel when the bracket swings from the finish-grinding position of the wheel into its truing position.

10 It is an object of my invention to design a machine of this type as a circular grinding machine.

To this end, in combination with the parts aforesaid, I provide means for imparting relative reciprocation to the grinding wheel and the work in the direction of their axes, for instance, means for reciprocating the slide in which the work is held, and means controlled by the reciprocation, for instance, a cam and a pawl-and-ratchet mechanism, for swinging the bracket stepwise at the end of one of the strokes making up the reciprocation.

The swinging movement imparted to the grinding wheel through the bracket must be such that 25 the grinding wheel moves at least as far as the minimum distance from the truing tool and from the work.

By designing a grinding machine in conformity with my invention, the work, for instance, a cylinder, is ground true and exactly to size merely by 30 swinging the grinding wheel.

In the accompanying drawings a machine embodying my invention is illustrated somewhat diagrammatically by way of example.

35 In the drawings:

Fig. 1 is an elevation of the machine showing the position of its parts after the insertion of a fresh workpiece,

Fig. 2 is a plan view of the machine, and 40 Figs. 3, 4, and 5 are elevations like Fig. 1, showing, respectively, the roughing, truing, and finishing position of the machine.

Referring now to the drawings, the machine is equipped with a base plate 1 having at one side a bearing for a shaft 9, and at the other side a rib presenting an inverted V guide for the work slide 2. Reciprocation may be imparted to the slide by any suitable means. In the present instance, a shaft 28 is mounted to rotate below the inverted V guide and equipped with a threaded portion 29 engaging in a female thread in a downward extension of the slide. By reversing the spindle 29, for which any suitable automatic mechanism known in the art and not illustrated, 55 may be provided, the work slide 2 is reciprocated

as indicated by the arrow 3 in Fig. 2. A groove is made in the rib in parallel relation to the inverted V guide, and another downward extension of the slide 2, with a wedge 23 at its lower end, projects into the groove.

5 Mounted on the work slide 2 is a motor 4, Fig. 2, which, through suitable means such as a worm gear and a driver, rotates the work 5 shown as a cylinder between a pair of centers.

A lug 6 projects upwardly from the work slide 10 2 and a truing tool having a knurled handle 7 and a point 8, is adjustably secured in the extension.

A bracket 10 is mounted to swing about the 15 shaft 9 on the base plate 1 and is supported by a cam 11. The cam is keyed on a shaft mounted in a bearing on the base plate 1. A grinding-wheel carriage 13 is mounted to slide on the bracket 10 and is adjusted by a spindle 12 connected to its lower end and provided with a hand 20 wheel. Mounted at the upper end of the carriage is the shaft 25 of a grinding wheel 14. The grinding-wheel shaft 25 is driven from a motor 19 on the carriage 13 by pulleys 15 and 16, and a belt 16. By these means, the grinding wheel 14 is rotated in the direction of the arrow 17.

The cam 11 which supports the swinging bracket 10, is turned stepwise by a pawl-and-ratchet mechanism. A double-armed lever 22 is fulcrumed on the base plate 1 and is so arranged 30 that its right-hand end is engaged and depressed by the wedge 23 of the work slide 2 when the slide has completed one of its strokes. A pawl 21 is pivoted to the left-hand arm of the double-armed lever 22 and is drawn into the teeth of a 35 ratchet wheel 20 on the shaft of the cam 11 by a spring. By these means, the cam 11 is turned in the direction of the arrow 26 for the angle corresponding to one pitch of the ratchet wheel 22, as often as the wedge 23 strikes the double-armed 40 lever 22.

The operation of the machine will now be described, it being assumed that a cylinder 5 having the initial diameter shown in Fig. 1, is reduced to the final diameter shown in Fig. 5. The proportion of the two diameters has been much exaggerated in the drawings.

The grinding-wheel carriage 13 is adjusted by means of the spindle 12, and the truing tool is adjusted by its handle 7, until the perimeter of 50 the grinding wheel 14, and the point 8 of the tool, are on the arc 24 of a circle about the axis of the swinging shaft 9. The arc 24 is tangent to the finish-ground work piece 5, Fig. 5.

At the beginning of the operation, Fig. 1, the 55

cam 11 holds the bracket 10 in such a position that the grinding disk 14 is off the work 5, and so a fresh piece 5 is readily inserted in this position.

- 5 The motors 4 and 19 are now started, and the work 5 and the grinding wheel 14 are rotated by the means described. The cam 11 is turned through one pitch of the ratchet teeth as often as the work slide 2, during its reciprocation, arrives 10 at the end of one of its strokes. Upon the stepwise turning of the cam 11 in the direction of the arrow 26, the bracket 10 and the grinding wheel 14 are gradually lowered in the direction of the arrow 27 in Fig. 1 until the grinding wheel bears 15 against the work 5 from above, Fig. 3. The work is now ground while the work slide 2 is reciprocated, and the cam 11 turned stepwise in the direction of arrow 26. As often as the work slide 2 arrives 20 at the end of one of its strokes during its reciprocation in the direction of the arrow 3, the cam 11 is turned, as described, allowing the bracket 10 and the grinding wheel 14 to descend. The work 5 is now roughed until it has nearly the final diameter, Fig. 5. Since the cam 25 11 is fed at one end of a stroke performed by the work slide 2, the wheel is moved nearer the work when it is at one end of the work, or it may even be moved beyond this end of the work.

When the work 5 has been roughed, the cam 11 30 gradually moves the grinding wheel 14 away from the work in upward direction, against the arrow 27. Before the grinding wheel 14 arrives in its topmost position, Fig. 4, the carriage 13 is advanced, by the spindle 12, for a distance at least 35 equal to the wear it has undergone during the roughing of the work 5. In the topmost position, the grinding wheel 14 is nearest the truing tool, the axes of the shafts 9, 25, and the point 8 of the tool being positioned in a straight line. The 40 grinding wheel 14 is now trued by the point 8 moving across it as the slide 2 reciprocates.

The trued grinding wheel is lowered by the cam 11 along the arc 24 which, as described, is tangent to the work 5 and extends through the 45 point 8 of the tool. The work 5 is now finished, and the finishing cut is completed when the axes of the shafts 9, 25, and the axis about which the work 5 is rotated, are in a straight line, as shown in Fig. 5. Preferably, the downward movement of the grinding disk 14 is continued beyond the straight-line position in order to make 50 sure that the work 5 has been finished to the required diameter throughout, and that this diameter is nowhere exceeded.

55 After the work 5 has been finished, the grinding wheel 14 is returned into the position Fig. 1, the finished work is removed and a fresh work piece is inserted.

The work is finished exactly true and exactly to 60 size all over its length by simply swinging the

grinding wheel 14 by means of the stepwise turning cam 11, as described.

The circular grinding machine according to my invention, besides the simplicity of its operation, as stated, possesses various other advantages over the known circular grinding machines. One of these is that it is not necessary to retract the carriage with the grinding wheel after a work-piece has been finished, to prevent damage to the grinding wheel by placing it against the work 10 at the full thickness of the grinding allowance.

Another advantage of my machine is that the angle through which the grinding wheel is swung, may be varied without deteriorating the accuracy of the work, as against known circular grinding machines in which the grinding-wheel carriage must only be advanced so far that not more than the grinding allowance is removed.

Still another advantage of my machine is that its operation is automatically subdivided into a 20 roughing and a finishing period, without varying the movement of the grinding wheel toward the work.

It is understood that the range of usefulness of my machine is not limited to the grinding of a 25 solid cylinder, as described, but that my invention also includes other machines such as inside grinders, or grinders without centers.

I claim:

1. In a circular grinding machine, a base plate, 30 a bracket mounted to swing on the base plate, a grinding wheel mounted to rotate on the bracket, a truing tool arranged with its point on the arc of a circle described by the perimeter of the grinding wheel, and tangent to the finish 35 diameter of the work, a work slide on the base plate, means for imparting relative reciprocation to the grinding wheel and the work on the slide, in the direction of their axes, and means controlled by the reciprocation for swinging the 40 bracket stepwise at least as far as the positions where the grinding wheel is nearest to the truing tool, and to the work, and for performing such stepwise swinging at the end of one of the strokes making up the reciprocation. 45

2. In a circular grinding machine, a base plate, a bracket mounted to swing on the base plate, a grinding wheel mounted to rotate on the bracket, a truing tool arranged with its point on the arc of a circle described by the perimeter of the 50 grinding wheel, and tangent to the finish diameter of the work, a work slide on the base plate, means for reciprocating the work slide, and means controlled by the work slide for swinging the bracket stepwise at least as far as the positions where the 55 grinding wheel is nearest to the truing tool, and to the work, and for performing such stepwise swinging at the end of one of the strokes making up the reciprocation.
